UNITED STATES PATENT OFFICE.

JAMES W. CARVER, OF PAWLET, VERMONT, ASSIGNOR TO HIMSELF, AND
GIBBONS L. KELTY, OF BROOKLYN, NEW YORK.

DESIGN FOR AN AX-HANDLE.

SPECIFICATION forming part of Design No. 18,881, dated January 29, 1889.

Application filed October 5, 1888. Serial No. 287,321. Term of patent 7 years.

To all whom it may concern:

Be it known that I, JAMES WOOD CARVER, of Pawlet, in the county of Rutland and State of Vermont, have invented a Design for a Handle for Axes and Similar Implements, of which the following is a specification.

The design of the shape and configuration of this handle is represented in the accompanying drawings, in which—

10 Figure 1 is a side view of the same. Fig. 2 is a cross-section in nearly full size at the line $x\ x$, and Fig. 3 is a similar cross-section at the line $y\ y$.

The ax-handle is elliptical in its cross-section, as illustrated in Figs. 2 and 3. The end A is adapted to the tool with which the handle is to be used, and does not form a necessary part of the present design. The contour of the handle is curved longitudinally from

15 the portion A to the projection B, and it is also tapering, as represented. The hand portion C of the handle is in the form of a bulb, being elliptical in section and a half-ovoid at

the back portion and tapering toward a part marked B, Fig. 1. This shape and configuration of handle is artistic in appearance and convenient for the hands of the party using the same.

20 The cross-sections of the handle at all points are elliptical, and a central plane passing longitudinally of the handle coincides with the longest diameters of the ellipses, the longitudinal curved contour being in this plane.

I claim as my invention—

25 The design of the shape and configuration of the handle, as represented, the same consisting in the design of the curved tapering portion and the bulb, that is a half-ovoid at the back end and elliptical in sectional shape, as represented.

30 Signed by me this 27th day of September, 1888.

JAMES W. CARVER.
